UNITED STATES PATENT OFFICE.

TIMOTHY B. RIDER, OF FITCH BAY, QUEBEC, CANADA.

INDICATOR FOR STEAM-BOILERS.

SPECIFICATION forming part of Letters Patent No. 234,146, dated November 9, 1880.

Application filed February 25, 1880.

To all whom it may concern:

Be it known that I, TIMOTHY B. RIDER, of Fitch Bay, Quebec, Canada, have invented a new and Improved Indicator for Steam-Boilers; and I do hereby declare that the following is a full, clear, and exact description of the same.

The object of my invention is to provide an improvement in the class of automatic safety attachments for steam-boilers, whose function is to dampen or extinguish the fire by allowing escape of water from the boiler into the fire-box in case the water becomes too low or the steam-pressure too high for safety.

I employ a tank containing a float and lever which operate a valve that controls escape of water to the fire-box, as heretofore; but I have so constructed and arranged these parts as to make the apparatus more compact, less liable to get out of order or become inoperative, and more efficient generally.

The details of construction and arrangement are as hereinafter described, reference being had to the accompanying drawing, in which I have represented a vertical section of my apparatus attached to a boiler and furnace front.

A indicates a water chamber or tank, which is attached to the front of a steam-boiler, B, by means of pipes C D, so that the water-level will always be the same in both. Within the tank is a hollow float, E, and a hinged lever, F. The float is made hollow to give it the greatest buoyancy practicable, and is preferably constructed of metal, but may be made of wood. In any case I construct its lower side thicker than the upper, so that practically it is weighted, and its vertical action or movement thereby rendered steadier.

The float is provided with conical projections a, which serve as guides in its vertical movement, also lessen the friction which the float would otherwise have with the sides of the tank, besides allowing sufficient space between them for free passage or circulation of water, so that, as the final result, the float has a freer up- and -down movement than would be otherwise practicable.

The lever F is hinged loosely to the side of the tank A, and connected with the tapered stem b of valve G in such a manner that

some vertical play or freedom of movement is allowed for the purpose of preventing the valve being disturbed or partially unseated by the slight oscillations of the float incident to the action or force of currents of water in the tank.

The float E is attached to and supported by a concavo-convex rest, H, having a slotted stem, d, which is pivoted to the free end of the curved float-lever F, so that it is allowed a certain freedom of lateral oscillation in the direction of the length of said lever.

By the above construction and arrangement of parts I secure important advantages in respect to economy of space, weight of parts, and buoyancy and effectiveness of the float over other apparatus of like general character.

The stem of the valve is tapered, and its seat beveled to prevent the collection of sediment therein, so that the escape of water or steam through the valve-orifice e is not obstructed in case of danger of explosion.

The conical lower end of the valve G bears upon one end of lever I, is pivoted horizontally in a case, J, whose opposite or free end is weighted to hold the valve normally to its seat. When the water becomes too low in the boiler B and tank A, or the pressure of steam passes the limits of safety, the falling of the float E or downward pressure of the water on the valve G will cause the weighted lever to be overbalanced, and by opening of the valve allow escape of the water into case or box J, and thence into the fire-box (not shown) of the boiler, thereby dampening or extinguishing the fire, and almost instantly arresting the generation of steam, partly or wholly, so that danger of explosion is avoided.

What I claim as new is—

The combination, with the tank A and pipes leading to the boiler and fire-box, of the pivoted lever F, the valve G, and the float and its concave rest H, having the slotted stem d, which is pivoted to the free end of said lever, all as shown and described, to operate as specified.

TIMOTHY BYRON RIDER.
